AUTOMATIC VOLUME CONTROL CIRCUIT

Lester T. Fowler, Oaklyn, N. J., assignor to Radio Corporation of America, a corporation of Delaware

Application December 16, 1933, Serial No. 702,676

7 Claims. (Cl. 250—20)

My present invention relates to amplification control circuits, and more particularly to a novel and improved type of delayed automatic volume control arrangement for a radio receiver.

In the past delay action has been secured in radio receivers employing automatic volume control arrangements by utilizing the self-biasing resistor in the cathode circuit of the controlled tubes. This self-biasing resistor supplied the initial grid bias for the controlled tubes when no bias voltage was being supplied from the automatic volume control tube. The self-biasing resistor was of such magnitude as to supply the normal grid bias for the controlled tubes at the voltages used, and to supply a degree of delayed automatic volume control action. Such delayed automatic volume control action occurred when a signal caused the automatic volume control to start operating and supply a negative control voltage to the grids of the controlled tubes, the plate current of said tubes then decreasing. This resulted in a decrease in voltage drop across the self-biasing resistors in the cathode circuits of the controlled tubes. Since this decrease in voltage drop was in a direction to initially oppose the action of the automatic volume control tube, there was thus supplied a delayed action for the automatic volume control. As soon as the voltage from the automatic volume control tube overcame the negative bias supplied by the self-biasing resistor, the automatic gain control action commenced in normal fashion.

Although such prior arrangements were of value, since existing circuit elements could be utilized to accomplish the delayed automatic volume control action, it was recognized that the delay action of the automatic volume control could be improved by increasing the value of the self-biasing resistor in the cathode circuits of the controlled tubes, and then "bucking down" the excess bias voltage developed by supplying a positive voltage to the grids of the controlled tubes from some other potential source. Such an arrangement is described, for example, by A. W. Barber in U. S. Patent No. 1,903,542, issued April 11, 1933, and is generically claimed therein. In the aforesaid Barber patent the bucking positive potential is specifically derived from an auxiliary battery.

It is one of the main objects of my present invention to provide an improved type of delayed automatic volume control receiver wherein the self-biasing resistor in the cathode circuit of a controlled amplifier is utilized to secure the delay

action, the bias resistor being of an abnormally high value for this purpose, and the excess negative bias voltage developed by the self-bias resistor being reduced by supplying a positive voltage to the grid of the controlled tube without utilizing any auxiliary batteries.

Another important object of the present invention is to provide an automatic volume control arrangement for a radio receiver wherein the action of the volume control arrangement is delayed until the signals impressed upon the receiver assume a predetermined intensity, the delay action being secured by utilizing a self-bias resistor in the cathode circuit of at least one high frequency amplifier, the self-bias resistor having a magnitude which is abnormally high, the excess negative bias developed across said self-bias resistor being compensated for by a positive grid potential developed across a second resistor disposed in the direct current path between the controlled amplifier and the negative side of the aforementioned self-bias resistor.

Still other objects of the present invention are to improve generally the simplicity and efficiency of delayed automatic volume control arrangements for radio receivers, and especially to provide an arrangement of this type which is not only reliable in operation, but economically manufactured and assembled in a radio receiver.

The novel features which I believe to be characteristic of my invention are set forth in particularity in the appended claims. The invention itself, however, both as to its organization and method of operation, will best be understood by reference to the following description taken in connection with the drawing in which I have indicated diagrammatically a circuit organization whereby my invention may be carried into effect.

Referring now to the accompanying drawing, there is shown a conventional type of superheterodyne receiver which embodies one form of the present invention. This receiver is of a type well known to those skilled in the art, and for this reason only such circuit elements will be described which are essential to a clear understanding of the invention. The receiver comprises the usual signal collector device, such as a grounded antenna circuit A, the latter being coupled to the tunable input circuit of the radio frequency amplifier tube 1, which may be of the screen grid type. The numeral 2 designates an intermediate frequency amplifier tube which has a resonant input circuit tuned to the operating intermediate frequency. The numeral 3 designates any well known type of frequency changing network which

is customarily utilized between the radio frequency amplifier of a superheterodyne receiver and the intermediate frequency amplifier. For the sake of simplicity of description, the network 3 is shown as of the composite first detector-local oscillator type. The numerals 4 and 5 designate the tunable signal circuits of the radio frequency amplifier and the frequency changer networks respectively, while the numeral 6 designates the tunable local oscillator circuit of the network 3. The dotted line 7 is to be understood as representing any well known type of mechanical uni-control which can be used to adjust the variable tuning condensers of the tuned circuits 15 4, 5 and 6.

The electron discharge tube 8 is a multiple duty tube known as a duplex-diode triode, and its associated circuits, as well as the specific construction of the tube, have been described and claimed by T. M. Shrader, in his application Serial No. 622,140, filed July 12, 1932, Patent No. 2,058,834, October 27, 1936. For the purpose of the present application it is sufficient to point out that such a tube comprises a pair of diode sections and a triode section, a common cathode being utilized for these three sections. In the present case the two diode anodes are strapped together and cooperate with the common cathode to provide a diode rectifier circuit whose tuned 25 input circuit 9 is resonant to the operating intermediate frequency and is coupled to the tuned output circuit 10 of the intermediate frequency amplifier tube. The resistor 11 is disposed in the diode rectifier circuit between the common cathode of tube 8 and the low alternating current potential side of tuned circuit 9, the resistor 11 being shunted by a radio frequency signal by-pass condenser.

The triode section of tube 8 functions as an 40 audio frequency amplifier, and the signal grid thereof may be connected to the negative side of resistor 11 through a radio frequency choke coil 12, a radio frequency by-pass condenser being connected between the cathode of tube 8 and the 45 grid side of choke 12. The grid of tube 8 has impressed upon it the audio frequency component of the rectified signal currents, the grid also being diode biased by virtue of its connection to the negative side of the resistor 11. The amplified 50 audio frequency potential component flowing in the triode section of tube 8 is transmitted to a succeeding audio frequency amplifier network, for amplification and utilization by a reproducer, through a coupling condenser 13.

The anode of the triode section of tube 8 is connected for direct current potential to the receiver potential supply source B (which is not shown to preserve simplicity of disclosure), the space current path of the triode section of tube 8 55 including a resistor R₂, this resistor being shown connected between the cathode of the tube and ground. It will be understood, of course, that the ground side of the resistor R₂ will connect back to the minus terminal of the potential supply source B. The anode circuits of tubes 1 and 2 are shown connected to the potential supply source B, and here again it will be clearly understood that the cathode circuits of the tubes 1 and 2 return to the negative sides of these potential supply sources. Of course, a common potential supply source may be used for tubes 1, 2 and 8. Appropriate radio frequency by-pass condensers are utilized in tubes 1, 2 and 8 at points well known to those skilled in the art.

70 75 The resistor R₁ is a self-bias resistor for the

signal grids of tubes 1 and 2, this resistor being connected between ground and the cathode of tube 1. The lead 14 connects the cathode of tube 2 to the cathode side of resistor R₁. It will, therefore, be seen that the resistor R₁ is disposed in the space current paths of each of amplifier tubes 1 and 2. It is within the scope of the present invention to employ a self-bias resistor in the cathode circuit of amplifier tube 2 which is independent of the self-bias resistor in the cathode circuit of tube 1. The signal grid of amplifier tube 1 is connected to the negative, or ground, side of resistor R₁ through a path which includes the lead 15, the resistor 11 and the resistor R₂, the signal grid of amplifier tube 2 being connected to the lead 15 through a lead 15'. The lead 15 functions as the automatic volume control lead, and for this reason is designated by the letters "AVC". The leads 15' and 15" include resistors for suppressing the audio frequency ripples in the automatic volume control connection, and the reference numerals 16 and 16' designate such ripple suppressor resistors.

As the signal energy impressed upon the diode detector tuned circuit 9 increases, the point 11' of resistor 11 increases in negative direct current potential, and, therefore, the signal grids of controlled amplifiers 1 and 2 become more negative in direct current potential with respect to their respective cathodes. This results in a decrease 30 in the gain of the controlled amplifiers, the reverse action taking place when the signal intensity decreases from maximum intensity towards minimum intensity. The sensitivity of the controlled amplifiers 1 and 2 are a maximum when 35 no signals are impressed upon the receiver. It is desirable to delay the automatic volume control action until signals of a predetermined intensity level are impressed upon the receiver. The reasons for such delay action are too well known to 40 those skilled in the art to require an explanation. As stated heretofore, the self-bias resistor of the controlled amplifiers supplied a degree of such delay action in receivers utilizing automatic volume control in the past. In the aforesaid Barber 45 patent, however, it was shown how such simple delay action could be greatly improved by increasing the value of the self-bias resistor in the cathode circuits of the controlled amplifiers, and "bucking out" the excess negative bias developed 50 because of this increased resistor value by using a positive potential derived from an auxiliary voltage source.

In the present arrangement the need for such an auxiliary battery is entirely eliminated, and 55 the improved delay action secured. It will be observed that the signal grid of each of the controlled amplifiers 1 and 2 is connected to the negative side of the self-bias resistor R₁ through a path which includes the resistor R₂. In effect 60 the signal grids of the controlled amplifiers are connected to the positive side of the resistor R₂, and for this reason the potential drop across the resistor R₂ is opposed to the negative grid biasing voltage developed across resistor R₁.

Since this "bucking" positive potential is secured by merely disposing a resistor of appropriate value in the cathode circuit of the triode section of the tube 8, it will be seen that the excessive negative biasing potential developed across 70 the self-bias resistor has been eliminated in a simple and effective manner. The values of the resistors R₁ and R₂ will depend upon the amount of delay action desired in the automatic volume control arrangement. In an actual embodiment 75.

of the invention the resistor R_1 had a value of the order of 850 to 1000 ohms, and the value of the resistor R_2 was chosen so as to provide a compensating positive potential sufficient to bring the effective grid bias potential for tubes 1 and 2 down to the value which will be supplied by the usual 200 ohm self-bias resistor. It will be observed that the tube 8 functions as a combined second detector, automatic volume control 10 rectifier and audio frequency amplifier. The diode circuit which includes the tuned circuit 9 functions as the second detector as well as the automatic volume control rectifier.

With regard to specific voltages, and assuming 15 that a normal negative bias of -3 volts is required on the signal grids of tubes 1 and 2, the controlled amplifiers, the value of resistor R_1 may be sufficiently high to develop a negative potential of -10 volts on the signal grids of tubes 1 and 2. In that case, the value of resistor R_2 will be so chosen that the cathode of tube 8 is raised 20 7 volts above ground, and for this reason the signal grids of the controlled amplifiers will have an effective normal bias of -3 volts. It will, therefore, be seen that in the present invention the self-bias resistor is deliberately made of an abnormally high value, and that the excess negative grid bias voltage which results is eliminated by utilizing a compensating positive potential 25 which is impressed upon the signal grids of the controlled amplifiers, this compensating positive potential being developed across a resistor disposed in the space current path of the audio amplifier network.

30 The actual bias on the controlled amplifier grids is the difference between the voltage drop across the resistor R_1 and that across the resistor R_2 (when no signal is being received and there is no drop across resistor 11). When the automatic volume control arrangement commences to 35 function, the plate current of the controlled amplifiers decreases, but since the drop across the biasing resistor R_1 is initially greater than in the case where the self-biasing resistor is of normal value, the action of the automatic volume control is delayed further.

A further detailed explanation of the delay feature is as follows: First assume the case where no signal is being received. No current is 40 flowing in the diode circuit so there is no voltage drop across resistor 11. Hence, the bias on the controlled tubes is the difference between the drops across R_1 and R_2 , and the value of these resistors is so adjusted that the bias is correct to 45 give maximum sensitivity with the voltages used. Now when a signal is received, rectification occurs in the diode circuit and automatic volume control voltage appears across resistor 11. This voltage is in a direction to bias down the controlled tubes. This action reduces the space current of the controlled tubes flowing through R_1 , which reduces the voltages across R_1 . This reduction in voltage across R_1 is the important point, since it is in a direction to oppose the 50 action of the automatic volume control voltage across resistor 11. The voltage across resistor 11 is tending to bias the tubes off and reduce the amplification of the controlled tubes, but the decreasing voltage across R_1 due to this action is 55 tending to reduce the negative bias of the controlled tubes and to hold the amplification nearly constant. Therefore, a valuable amount of delay takes place as long as the voltage across R_1 is appreciable with respect to the voltage across 60 resistor 11.

Now when a very strong signal is tuned in, the voltage across resistor 11 rises to a relatively large value, and the space current of the controlled tubes is reduced to such an extent that the voltage drop across R_1 becomes very small. After this happens no further delay takes place 5 because the drop across R_1 is substantially zero insofar as the automatic volume control action is concerned. The space current of tube 8 is fed through a high resistance from the B+ terminal 10 of the plate supply source. This resistance is several times the tube impedance, and so is largely instrumental in determining the space current flow of tube 8. Therefore, the bias voltage of tube 8 may vary over a fairly wide range before 15 the space current is appreciably affected. Of course, if enough negative bias is applied to the grid of tube 8, its space current is eventually cut off. However, the present delayed AVC action is concerned only with the first few volts appearing 20 across resistor 11, that is to say, when it is desired that the delay action take place. Accordingly, with the space current of tube 8 remaining practically constant for the first few volts appearing across resistor 11, the voltage drop across 25 resistor R_2 will remain practically constant, and the delay action described above will take place.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:—

1. A radio receiver including a high frequency amplifier provided with a tunable input circuit, a self bias resistor in the cathode circuit of said amplifier, said resistor having an abnormally high magnitude whereby it develops excessive negative grid bias for the amplifier, a rectifier coupled to the amplifier for producing a direct current voltage from amplified signal energy, a resistor in the rectifier circuit for developing said voltage, an automatic volume control connection between the rectifier resistor and the amplifier grid, an electron discharge device having a grid connected to a point on the rectifier resistor, a third resistor in the space current path of said device, and connections between the first resistor and the third resistor whereby the voltage developed across said third resistor is opposed in sign to the said excessive grid bias.

2. A radio receiver including a high frequency amplifier provided with a tunable input circuit, a self bias resistor in the cathode circuit of said amplifier, said resistor having an abnormally high magnitude whereby it develops excessive negative grid bias for the amplifier, a rectifier coupled to the amplifier for producing a direct current voltage from amplified signal energy, a resistor in the rectifier circuit for developing said voltage, an automatic volume control connection between the rectifier resistor and the amplifier grid, an electron discharge device having its grid connected to a point on the rectifier resistor, a third resistor in the space current path of said device, means for connecting the first and third resistors in such a manner that the voltage across the third resistor is opposed in sign to said grid bias, the voltage developed across said third resistor being of a lesser magnitude than said grid bias.

3. In a carrier wave receiver, the combination

75

with a carrier wave transmission tube, a diode rectifier having input and output impedances associated therewith, means coupling the transmission tube output circuit to the input impedance of said diode rectifier, and circuit elements for transferring back to said transmission tube a gain control voltage developed across the output impedance of said diode rectifier, of a control grid bias resistor in said tube cathode circuit of such magnitude as substantially to postpone reduction in transmission tube gain until said gain control voltage reaches a predetermined value, means including serially in a direct current path having the diode cathode as an element thereof for developing a voltage of lesser magnitude than the voltage across the bias resistor, and connections between the bias resistor and the last means whereby the lesser voltage is opposed to said bias voltage.

4. An electrical wave transmission system of the type including an amplifier and a rectifier for impressing upon said amplifier a control grid bias potential varying automatically with changes in the amplitude of the electrical waves impressed upon said amplifier, characterized by the fact that the cathode circuit of said ampli-

fier, includes a bias resistor across which the space current flow establishes a bias potential, said resistor having a magnitude such that for a predetermined range of amplifier input voltages the changes in cathode bias potential substantially offset changes in the rectifier bias potential, an audio amplifier having its input electrodes coupled to said rectifier, an impedance in the space current of the audio amplifier, and connections between the impedance and the bias resistor such that voltages across the two are in opposition. 5

5. In a receiver as defined in claim 1, the grid of said amplifier being connected to said bias resistor through a path including said automatic volume control connection and the third resistor. 15

6. In a receiver as defined in claim 1, said rectifier and device being included in a common tube envelope and the electrodes thereof having a common cathode. 20

7. In a receiver as defined in claim 2, said device comprising an audio amplifier, and the electrodes of the rectifier and audio amplifier being disposed in a common tube envelope. 25
